UNITED STATES PATENT OFFICE.

SYDNEY C. LEGH, OF OBERHOFEN, SWITZERLAND, ASSIGNOR OF ONE-HALF TO CHARLES A. GIFFORD, OF SUMMIT, NEW JERSEY.

PLAYING-CARDS.

1,007,460.

Specification of Letters Patent. Patented Oct. 31, 1911.

Application filed January 5, 1911. Serial No. 600,958.

To all whom it may concern:

Be it known that I, SYDNEY C. LEGH, a subject of the King of England, residing at Oberhofen, Lake Thun, Switzerland, have invented certain new and useful Improvements in Playing-Cards; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in playing cards; and, the present invention relates, more particularly, to that class of playing cards known in the art as squeezers, in which the card value is upon the full face of the card, as well as in miniature upon the margin of the card, so that the player can easily read the values of the respective cards when held in the hand and when arranged in a fan-like or other close order. In playing cards of this character, it is a fact, that the mental image given by this miniature arrangement of the card-values, in the form of "pips", or letters or figures, is not so clear that the average player dare trust to it, and the player will, therefore, either keep the cards in the hand in open order, thus foregoing the help offered by the marginal indications of the card-values; or, in critical movement, to be quite sure, the player will shuffle the cards across his or her field of vision, so as to catch a glimpse of the full face of a card or of all the cards in the hand.

The present invention has for its principal objects:—first;—to remedy this defect by making the closely arranged cards in the hand easily and quickly readable, and thereby making the squeezers really efficient and the marginal indications practicable for the purposes for which they are intended; and, secondly, to distinguish readily between the two suits of the same color, as for instance between hearts and diamonds and between clubs and spades, not only when the cards are held in the hand, but also when face up on the table.

Other objects of this invention not at this time more particularly enumerated will be clearly evident from the following detailed description of the present invention.

With the various objects of the present invention in view, the said invention consists in a pack or series of playing cards, the purposes of which are as follows: First;—the card-value as indicated by means of a continuous series of miniature "pips" or a "blaze" upon one or both of the margins of each card, commencing at the top left hand corner, and also at the lower right-hand corner; said arrangement or series of "pips" or "blazes" extending along the said edge or edges of the cards a distance proportionate to the number of "pips" or the length of "blaze" required to denote the value of each card, thus the 2 to 10 cards, being designated by a series of "pips" or a "blaze" from 2 to 10 units in length, respectively, and furthermore, the jack, queen, king and ace cards, being respectively indicated by a series of "pips" or "blazes" of 11, 12, 13 and 14 units. Secondly;—the suits of the same color may be distinguished by the "pips" or "blazes" being respectively printed positively and negatively, that is, the chain of "pips" in the heart and the club-suits may have the heart and club "pips" printed directly as to their forms in the usual red and black colors, while the chain of "pips" in the diamond and spade-suits may be indicated, as to their conformations in white upon a red or black "blaze" or marginal strip or band, respectively, so as to more easily distinguish the order of the cards. Thirdly;—the suits of the same color may be distinguished by means of a border, either ornamental or in solid color, or by the use of an "all over" design or background on the card, the marginal indications or "pips" or "blazes" to be printed either positively or negatively, as desired. And fourthly;—the suits of the same color may be distinguished by means of a background of solid color covering either the whole card or in the form of a wide margin, on which the spots or pips are displayed in white. Other arrangements of the series or chains of the "pips" or "blazes" may, however, be made without departing from the scope of the present invention, as for instance, the marginal "pips" may be printed with a slightly larger spacing after every alternate pip, thus forming them into pairs, to facilitate counting them.

Briefly, therefore, the present invention consists in a pack of playing cards, each

card having a graphic representation of the card value produced by printing, or otherwise, upon the margin of the card, a flare or blaze of color formed by a row or chain of miniature "pips" of like shape or conformation and of the same number, as the "pips" upon the full face of the cards, the jack, queen, king and ace, respectively, having rows or chains of 11, 12, 13 and 14 "pips"; and, furthermore, by printing or otherwise producing said rows or chains of miniature "pips" both positively and negatively, according to their suit-indications, and also by means of borders and back grounds to easily distinguish the suits of the same color from one another.

The invention is clearly illustrated in the accompanying drawings, in which:—

Figure 1 is a face-representation of an arrangement of thirteen cards, embodying the principles of the present invention, said arrangement of cards representing a whist-hand, and said figure showing the cards in their squeezed or closed order. Figs. 2 and 25 3 are face views of two playing cards, showing a modified arrangement of the chain of "pips," said figures representing the negative arrangement of the "pips" on a colored "blaze." Figs. 4, 5, 6, 7, 8 and 9, and 19 30 are face views of playing cards, showing several other modified arrangements of the chains of "pips," borders, backgrounds, etc., but all embodying the principles of the present invention.

Referring now to Fig. 1 of the drawings, the reference-character 1 indicates an arrangement of thirteen playing cards of the various denominations or card-values, and the reference-character 2 indicates the chains or "pips" printed or otherwise produced upon the marginal edges of the respective cards, said "pips" in this arrangement of cards all being made in the same colors as the usual corresponding and larger card-values upon the faces of the cards. It will be noticed from an inspection of said Fig. 1 of the drawings, that in no case is there less than a representation of two "pips" forming a row or chain of "pips." In this arrangement of cards all of the card-values have been shown, and thus:—The two of hearts is provided with a chain of two hearts in miniature; the three of diamonds is provided with a chain of three diamonds in miniature; the four of clubs is provided with a chain of four clubs in miniature; the five of hearts is provided with a chain of five hearts in miniature; the six of spades is provided with a chain of six spades in miniature; the seven of diamonds is provided with a chain of seven diamonds in miniature; the eight of clubs is provided with a chain of eight clubs in miniature; the nine of spades is provided with a chain of nine spades in miniature; the ten of dia-

monds is provided with a chain of ten diamonds in miniature; the jack of clubs is provided with a chain of eleven clubs in miniature; the queen of diamonds is provided with a chain of twelve diamonds in miniature; the king of spades is provided with a chain of thirteen spades in miniature; and the ace of diamonds is provided with a chain of fourteen diamonds in miniature. Of course it will be understood, that the other cards of the suits not shown in the hand of cards represented in said figure, are also provided with correspondingly arranged chains of "pips" in miniature, all forming a graphic representation of the card values ranging from a chain of two "pips," the lowest card-value, to a chain of fourteen "pips," the highest card-value. From an inspection of the hand-arrangement of the cards, it will be clearly evident, that the respective values of the cards, when arranged in suits, can be easily read at a glance, so that there is no necessity of holding the cards in the hand in an open order, or to shuffle the cards across the field of vision of the player, as may be necessary in critical moments, with the cards now in ordinary use, in order to catch a glimpse of the full face of a card or cards, so as to be sure that the proper play is made.

In Fig. 2 of the drawings is shown a card 3, the six of diamonds, provided with a "blaze" or band 4 corresponding in color to the color of the suit of the card, this "blaze" or band 4 being provided with a chain of "pips," as 5, negatively produced, and said chain of "pips" corresponding to the value of the card 3. One purpose of this arrangement of negative "pips" is that the diamond and spade suits can be easily distinguished from the heart and club suits, the said heart and club suits being provided with chains of "pips" of the positive arrangement indicated in said Fig. 1 of the drawings, or vice-versa.

In Fig. 3 of the drawings is shown a playing card 6, the face of which is provided with a small full card value representation, as 7, representing in this case, the seven of spades, said card 6 being provided with a marginal color-blaze or band, as 8, corresponding in color to the color of the suit of the card-value representation 7, the said "blaze" or band 8 being provided with a chain of "pips," as 9, negatively produced.

In Figs. 4 and 5 of the drawings are shown two cards 10 and 11, the ten of diamonds and the ace of spades, respectively, the complete faces of which are provided with the background 12, in red and black, respectively, according to the suit-value of the cards. The reference-character 13 in each case indicates the full card-value representations, which are negatively produced upon the blazed faces of the cards, and

the reference-character 14 indicating the graphic representations of the chains of "pips" corresponding to the values of said cards 10 and 11, said chains of "pips" being also negatively produced in both instances.

In Figs. 6 and 7 of the drawings is represented another modification, the playing cards being respectively indicated by the 10 reference-characters 15 and 16, the faces of said cards being provided with small or full-card representations, as 17, representing the three of spades and the two of diamonds, said cards 15 and 16 being provided 15 upon those portions which surround the said small full-card representations 17 with color-margins 18, corresponding to the suit-values of the respective cards, the said color-margins 18 being provided with chains of 20 "pips", as 19, in miniature and also negatively produced.

Referring now to Figs. 8 and 9 of the drawings, there is shown in said figures another modified construction of playing cards 25 showing an embodiment of the principal features of this invention. In said Figs. 8 and 9, the reference-characters 20 and 21 indicate two cards, the four of diamonds, and the four of spades, respectively. As 30 shown, in said Figs. 8 and 9 of the drawings, the negative suits, (diamonds and spades) in this case have a faint negative border, as at 22, which is carried around the cards in the form of lines which may 35 be straight, or wavy, or of any ornamental design. The card indicated in said Fig. 8 is also provided with a "blaze" 23 upon which is negatively indicated a chain of "pips", as 24, which indicates graphically 40 the card value. In Fig. 9 of the drawings, this "blaze" is omitted and the chain of "pips" is also indicated by the reference-character 24, and in the simple manner shown in Fig. 1 of the drawings.

In Fig. 10 is shown a card 25, in this case the ten of diamonds, which is provided with the usual arrangement of spots and a chain of "pips" as 26, all printed or otherwise produced upon an ornamental background, 50 as 27, which may be made in a lighter shade of color than the color of the chain of "pips", as will be clearly evident.

Of course, it will be understood, that any other means of differentiating the card-suits 55 from each other may be employed; that is, in lieu of the background being made in straight or wavy lines, the background may be of any desired design or ornamentation; and, furthermore, the coloring of the background, if desired, may be of a shade different 60 from that of the "spots" or of the marginal "pips" of the card. It will also be evident, that in lieu of the forms of color-background shown in Figs. 4, 5, 6 and 7 of 65 the drawings, these color-backgrounds may,

if desired, be of a different shade from the "spots" of the cards, or of the marginal "pips"; or, said color-backgrounds may be in any ornamental designs, which may be engraved or otherwise formed upon the 70 faces of the cards, as shown in Fig. 10.

I claim:—

1. A pack of cards comprising a series of card-suits, the cards of each suit being provided with graphic representations of the 75 card value formed by chains of miniature "pips," all arranged to show the graphic representation of the relative strength of each suit in hand by means of the lengths of said chains of "pips," including the face 80 cards and the high value of the ace.

2. A pack of cards comprising a series of card-suits, the cards of each suit being provided with graphic representations of the 85 card values formed by chains of miniature "pips" of like shape and of the same number as the spots upon the faces of the cards, all arranged to show the graphic representation of the relative strength of each suit in hand by means of the lengths of said chains 90 of "pips," including the face cards and the high value of the ace.

3. A pack of cards comprising a series of card-suits, the cards of each suit being provided with graphic representations of the 95 card values formed by chains of miniature "pips" of like shape and of the same number as the spots upon the faces of the cards, except the jack, queen, king, and ace, which are provided with marginal chains of 100 "pips" ranging from eleven, twelve, thirteen and fourteen "pips," respectively.

4. In a pack of playing cards comprising two sets of negative card suits, each card being provided with a marginal "blaze," 105 each "blaze" being provided with a graphic representation of the card value formed by a chain of miniature "pips" upon the "blaze," said chain of "pips" being negatively produced, and said "pips" being of 110 like shape as the spots upon the faces of the cards, all arranged to show the graphic representation of the relative strength of each suit in hand by means of the lengths of said marginal "blazes" and the "pips" thereon, 115 including the face cards and the high value of the ace.

5. In a pack of playing cards comprising two sets of negative card suits, each card being provided with a marginal "blaze," each 120 "blaze" being provided with a graphic representation of the card value formed by a chain of "pips" being negatively produced, and said "pips" being of like shape as the spots upon the faces of the cards, except the 125 jack, queen, king and ace, which are provided with marginal chains of "pips" ranging from eleven, twelve, thirteen and fourteen "pips," respectively, all arranged to show the graphic representation of the rela- 130

- tive strength of each suit in hand by means of the lengths of said marginal "blazes" and the "pips" thereon, including the face cards and the high value of the ace.
- 5 6. A pack of cards comprising a series of card suits, the higher or positive suits being distinguished from the lower or negative suits by having the faces of the one set of suits colorably distinguished from the faces of the other suits, and the cards of each suit being provided with graphic representations of the card-values formed by chains of miniature "pips," and the chain of "pips" in the negative suit-cards being negatively produced, all arranged to show the graphic representation of the relative strength of each 25 suit in hand by means of the lengths of said chains of "pips," including the face cards and the high value of the ace, substantially as and for the purposes set forth.
- 10 15 7. A pack of cards comprising a series of card suits, the higher or positive suits being distinguished from the lower or negative 30 suits by having the faces of the one set of suits colorably distinguished from the faces of the other suits, the cards of each suit being provided with graphic representations of the card-values formed by chains of miniature "pips," all arranged to show the graphic representation of the relative strength of each suit in hand by means of the lengths of said chains of "pips," including the face cards and the high value of the ace.
- 15 20 8. A pack of cards comprising a series of card suits, the higher or positive suits being distinguished from the lower or negative 35 suits by having the faces of the one set of suits colorably distinguished from the faces of the other suits, the cards of each suit being provided with graphic representations of the card-values formed by chains of miniature "pips," all arranged to show the graphic representation of the relative strength of each suit in hand by means of the lengths of said chains of "pips," including the face cards and the high value of the ace, substantially as and for the purposes set forth.

suits by having the faces of the one set of suits colorably distinguished from the faces of the other suits, the cards of each suit being provided with graphic representations 25 of the card-values formed by chains of miniature "pips," and the chain of "pips" in the negative suit-cards being negatively produced, all arranged to show the graphic representation of the relative strength of each 30 suit in hand by means of the lengths of said chains of "pips," including the face cards and the high value of the ace, substantially as and for the purposes set forth.

In testimony, that I claim the invention 35 set forth above I have hereunto set my hand this twentieth day of December 1910.

SYDNEY C. LEGH.
